DESIGN FOR A DRESS

Sally Cicardo, New York, N. Y.

Application November 6, 1937, Serial No. 72,647

Term of patent 3½ years

To all whom it may concern:

Be it known that I, Sally Cicardo, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the particular arrangement of nail head embroidery on the sleeves, simulated bolero and rear waist as shown.

I claim:

The ornamental design for a dress, substantially as shown, and described.

SALLY CICARDO.
